UNITED STATES PATENT OFFICE.

WILLIAM R. MILLER, OF BALTIMORE, MARYLAND.

LOAD-INDICATOR FOR MAGAZINES OF FIRE-ARMS.

SPECIFICATION forming part of Letters Patent No. 394,872, dated December 18, 1888.

Application filed June 30, 1888. Serial No. 278,651. (No model.)

To all whom it may concern:

Be it known that I, WILLIAM R. MILLER, of the city of Baltimore, and State of Maryland, have invented certain Improvements in Repeating Fire-Arms, of which the following is a specification.

This invention consists in providing a repeating-gun with a magazine having a sight-aperture, through which its contents may be inspected, and in covering the said aperture with a transparent plate and a protecting-shutter, as will hereinafter fully appear.

In the description of the said invention which follows reference is made to the accompanying drawings, forming a part hereof, and in which—

Figure 1 is an exterior side view of a gun provided with my invention; and Figs. 2 and 3 are enlarged sectional details of the same taken, respectively, longitudinally and transversely of the magazine. Fig. 4 is a longitudinal section of a part of a gun, illustrating a modification of the invention; and Figs. 5 and 6 are enlarged details of the same, also in section.

Similar letters of reference indicate similar parts in all the figures.

Referring to Figs. 1, 2, and 3, A, B, and C are respectively the stock, barrel, and magazine of the improved fire-arm.

D is the magazine-spring whereby the cartridges or shells a are fed. The magazine at a point near to the lock is provided with an opening, b, which in width is considerably less than the magazine and of a length about equal to a cartridge or shell. The position of the aperture b is preferably such as to expose the magazine-spring, or a portion of the same, when, say, one or two cartridges remain in the magazine; but it may be placed to show that three or even more cartridges are left in the magazine.

Over the opening b, I place a transparent plate, c, and over this plate a shutter, E. The shutter E consists of a bolt, d, confined in a tube, e, having two slots, f and g, situated diametrically opposite to each other. This tube is so placed and secured in the stock A that the opening b may be seen through the slots f and g. The bolt d is yieldingly held, so as to close the slots f and g, and also the opening b, by means of a spring, h, which is confined between one end of the bolt d and the head of the tube. The bolt may be slid back, so as to expose the slots f and g and the opening b by the finger through the medium of a pin, i.

In Figs. 4, 5, and 6, which represent parts of a gun in which the magazine is in the rear of the lock and barrel instead of in front of the lock, as in the other figures, the shutter consists of a hinged plate. This plate when closed is flush with the surface of the stock.

I claim—

1. In a repeating fire-arm, the magazine thereof having a slot or aperture through which its contents may be inspected, combined with a shutter to cover the said aperture and a transparent plate interposed between the said shutter and the perforated magazine, substantially as and for the purpose specified.

2. In a repeating fire-arm, the magazine thereof having a slot or aperture through which its contents may be inspected, combined with a shutter formed of a spring-bolt confined in a slotted or perforated tube embedded in the stock of the said fire-arm, substantially as and for the purpose specified.

WILLIAM R. MILLER.
